UNITED STATES PATENT OFFICE

HARRY T. KINGSBURY, OF KEENE, NEW HAMPSHIRE

TOY AIRPLANE LANDING GEAR

Original application filed June 19, 1929, Serial No. 372,128. Divided and this application filed January 7, 1930. Serial No. 419,112.

This invention relates to improvements in toy airplanes, and more particularly concerns details of construction and assemblage of such devices.

6 This application is a division of my pending application Serial No. 372,128, filed June 19, 1929 on toy airplane; and likewise has for an object to provide a toy airplane with a light body portion having its members 10 rigidly assembled and to which the undercarriage, wings, elevator and rudder members may be quickly and elastically attached, and from which they may be disconnected for ease in packing.

15 Another object of the present invention is to provide improvements in the undercarriage construction and assemblage with respect to the body which enables a simple and cheap manufacture of this portion, and an 20 ease in mounting upon the body, along with a functioning elasticity, in such manner that when the plane comes to ground, the underframe and associated parts yield to the impact without breakage.

25 A further object of the invention is to provide simple and rigid brace means for the body to enable it to support the strains of the band motor and of impact of any part of the 30 device with the ground or an obstacle.

35 Still another object of the invention is to provide a simple and cheap mounting for a rear wheel, so that the toy airplane will require less power and less distance of travel when running for a take-off.

40 With these and other objects in view, as will appear in the course of the following specification and claims, illustrative examples of the construction employed have been set forth on the accompanying drawings, in which:

Figure 1 is a plan view of the assembled airplane.

Fig. 2 is a corresponding side elevation.

45 Fig. 3 is a vertical longitudinal section substantially on line 3-3 of Fig. 1, upon an enlarged scale and showing the propeller mounting and the undercarriage mounting.

50 Fig. 4 is a view on a similar scale, showing the mounting of the rear wheel.

Fig. 5 is a detail perspective view of a portion of the undercarriage assembly.

Fig. 6 is a corresponding view of a modified form of undercarriage assembly.

In the drawings, the body comprises the two spars 10, 11 which extend longitudinally thereof and are slightly bowed from end to end so that their greatest distance apart is substantially at the point of attachment of the wings. At the front the ends of the spars 10, 11 are joined by a sheet metal clip 12 which is formed by folding a sheet of metal to provide sleeves 13 fitted over the ends of the respective spars 10, 11, the whole clip being bent into U-shape as seen in Fig. 1, with the central portion reinforced by the flanges 14 and provided with an aperture for the passage of the driving shaft 15 for the propeller. The sleeves 13 at their rear ends have each a projecting ear 16 spaced from the lower surface of the respective spar 10 or 11. Intermediate their length the spars are provided with a cross brace 17 likewise formed from sheet metal with reinforcing flanges and provided at the ends with the sleeves 18 which are fitted about the respective spars 10, 11 and preferably are held thereto by indentations 19 which depress the inner wall of the sleeve 18 into the structure of the respective spar. The connecting part of the metal brace 17 is curved downward to afford clearance for the band motor M. The forward ends of the sleeves 18 are provided with ears 20 which are spaced from the lower surfaces of the spars 10, 11.

The rear ends of the spars 10, 11 are connected by a clip 21 having the sleeves 22 formed at the ends thereof to receive the spars 10, 11 and being fixedly connected thereto. The ends of the sleeves 22 project beyond the ends of the spars, and the inwardly directed faces of the clip at this point are perforated to receive the axle pin 23 of the rear wheel R, which is received between the sleeves 22 in the U-shaped clip 21 (Fig. 95 4), while the walls of the sleeves 22 are crimped down to prevent lengthwise movement of the pin 23. The central portion of the U-shaped clip 21 is provided with two apertures through which passes the fixed 100

rear stay 24 for the band motor M, as shown in Fig. 4, whereby this stay is prevented from movement about its own axis.

The undercarriage comprises the axle shaft 25 which passes through the front wheels F so that these wheels may rotate freely therearound, and is provided with bent ends to prevent the wheels from coming off this axle. The undercarriage strut construction comprises a single piece of wire, substantially symmetrical about the central vertical longitudinal axis of the airship. The forward ends of the strut wire are bent inward and then upward to fit closely around the spars 10, 11 (Figs. 1 and 3), being received between the ears 16 and the respective spar 10 or 11. The strut wire extends relatively outwardly, rearwardly and downwardly from its forward end connection, to form the front struts 26, and then is provided with a plurality of convolutions 27 loosely surrounding the axle 25 so that the axle may turn within these convolutions as in a bearing. From these convolutions the strut wire extends upwardly, rearwardly and inwardly to form the rear struts 28, at the upper ends of which the wire portions just described are joined by the integral bridge 29 having a relative downwardly convex curvature to avoid the band motor M, and being provided with loops to fit between the ears 20 and the respective spars 10, 11 (Figs. 1 and 3), the angle between the planes of the curved portion 29 and of the rear struts 28 being such as to prevent lateral movement of the strut at its rear end. A retaining or stop member 30 is likewise formed of wire with symmetrical ends each comprising a bent portion 31 terminating in an eye 32 fitting about the axle 25.

The wire strut member is formed so that the convolutions 27 act as a torsion spring to force the strut members 26, 28 relatively away from one another in Fig. 2, so that when the undercarriage is removed from the body, it preferably has the struts 26 and 28 substantially in a plane for easy packing. To assemble the undercarriage to the body the struts 26, 28 are compressed beyond the position shown in Fig. 2, and the rear bridge 29 is slipped between the ears 20 and the spars 10, 11. The front ends 26a are then slipped between the respective clips 16 and spars 10, 11. The torsional effect of the convolutions 27 will now hold the undercarriage fixedly to the body. In alighting on the ground, the weight of the body coming upon the struts 26, 28 will force the convolutions 27 downward slightly, with a springy yielding of the axle 25; the stop member 30 prevents the spreading of the convolutions 27 laterally under such conditions and thus prevents a binding or braking of the front wheels F.

65 The wing assembly comprises the two sym-

metrically formed wing surfaces 33, 34 which are curved upwardly as usual, and are preferably formed of thin veneer wood. The front edges of these wings are protected by reinforcing strips 35, and the curvature of the wings is preferably maintained by the provision of channel shaped sheet metal ribs 38 having ends 39 bent over the edges of the wings to hold the ribs in position. The two wings 33, 34 are joined at their centers at 75 a dihedral angle by the thin sheet metal plates 40, 41 which fit over the undersurface of the wings and are secured together by eyelets 42 which are formed from the member 40 and pass through the wing surfaces to be 80 clamped to the member 41. This produces a very simple, light and cheap assembly. The wings are held in position by wing block wires 46 which connect the light wood blocks 45; and by rubber bands 48 passed around the respective spars from beneath, and over the blocks 45 to hold the blocks and wings together. It will be noted that since the rubber band is under tension, it tends to pull the blocks 45 slightly closer together, thus engaging them against the edges of the wing and holding the wing in an adjusted position.

90 The elevator 50 is preferably of a thin sheet of veneer wood cut to appropriate shape and mounted loosely upon the spars 10, 11. The rudder 51 is likewise preferably of thin veneer wood cut to a desired shape and provided at its bottom with a sheet metal reinforcing member comprising the lugs 54, 55 which rest upon the elevator and serve to hold the rudder in its proper upright position. Rubber bands 58 pass around beneath the spars 10, 11 and over the top of the elevator, being respectively passed over the elevator and the lugs 54, 55 of the rudder, so that they serve not only to hold the elevator in position, but also to maintain the rudder upon the elevator.

100 The propeller is formed of two pieces of metal 100, 101 having peripheral stiffening beads 102 by which the parts are secured together in mutually overlapping relationship. The shaft 15 at the front end of the band motor M is passed through the propeller at its axis, and has a rebent end to assure the proper rotation of the shaft and propeller together.

110 In the modified form of axle assembly shown in Fig. 6, the axle 25a is provided with rebent and offset ends 25b to receive the wheels, the offset portion 31a itself providing a stop for limiting the spreading movement of the coils 27 which join the struts 26 and 28.

120 It is obvious that the invention is not limited to the form of construction shown and described, but that it may be modified in many ways within the scope of the appended claims.

What I claim as new and desire to secure by Letters Patent is:

1. In a toy airplane, longitudinally extending body spars having ears mounted thereon, and an undercarriage comprising front and rear parts and including means to force the upper ends of such parts resiliently away from one another, the upper portions of said parts being engaged by said ears and held in engagement therewith by such resilience.
2. A toy airplane as in claim 1, in which the undercarriage has said parts formed of wire with convolutions between the same to form a spring for said resiliency, and an axle journaled in said convolutions.
3. In a toy airplane, an undercarriage comprising a bent piece of wire forming the front and rear lateral struts and joined between the struts on either side by convolutions of the wire, an axle journaled in said convolutions, and a spread-preventing bar having a loop fitting around the axle outside of each convolution whereby to prevent the lateral spread of the convolutions under load.
4. In a toy airplane, a pair of longitudinally extending and laterally spaced body spars, transverse reinforcing members connecting said spars and provided with ears, and an undercarriage comprising front and rear parts and including means to force the upper ends of said parts resiliently away from one another, the upper portions of said parts being engaged by said ears and held in engagement therewith by such resilience.
5. In a toy airplane, longitudinally extending and laterally spaced body spars, transverse metal stiffening members connected to and holding said body spars spaced apart and including integrally formed downwardly depending ears, and an undercarriage comprising front and rear parts and including means to force the upper ends of said parts resiliently away from one another, the upper portions of said parts being engaged by said ears and held in engagement therewith by such resilience.

In testimony whereof, I affix my signature.

HARRY T. KINGSBURY.
